CLAIM

The ornamental design for a multiple level chess board system, as shown and described.

DESCRIPTION

FIG. 1 is a front perspective view of a multiple level chess board system in accordance with this invention, wherein the rear and side perspective views of the multiple level chess board system are identical to FIG. 1 and therefore not shown.

FIG. 2 is a top view of the multiple level chess board system of FIG. 1.

FIG. 3 is a bottom view of the multiple level chess board system of FIG. 1; and,

FIG. 4 is a front elevational view of the multiple level chess board system of FIG. 1, wherein the rear and side elevational views of the multiple level chess board system are identical to FIG. 4 and therefore not shown.

1 Claim, 4 Drawing Sheets
